(57) **CLAIM**

The ornamental design for a container for pouches of smokeless tobacco, as shown and described.

DESCRIPTION

FIG. 1 is a perspective view of a container for pouches of smokeless tobacco, according to our new design, wherein the lid and base are separated;

FIG. 2 is top perspective view of the lid portion thereof, with the lid compartment in the open configuration;

FIG. 3 is a top plan view of FIG. 1 in a closed configuration;

FIG. 4 is a side elevational view thereof, wherein the base and lid are separated;

FIG. 5 is a side elevational view thereof wherein the base and lid are shown in a closed configuration; and,

FIG. 6 is a top plan view of the base portion thereof, showing unclaimed environmental structure.

The broken lines in FIG. 6 showing pouches of smokeless tobacco in the container is included for the purpose of illustrating unclaimed subject matter only and forms no part of the claimed design.
